UNITED STATES PATENT OFFICE.

CARL H. KEUSCHER, OF JERSEY CITY, NEW JERSEY.

WATCH-CHAIN HOOK.

SPECIFICATION forming part of Letters Patent No. 732,358, dated June 30, 1903.

Application filed March 31, 1903. Serial No. 150,379. (No model.)

To all whom it may concern:

Be it known that I, CARL H. KEUSCHER, a citizen of the United States, and a resident of Jersey City, in the county of Hudson and State of New Jersey, have invented certain new and useful Improvements in Watch-Chain Hooks, of which the following is a specification.

The invention relates to improvements in watch-chain hooks; and it consists in the novel features and construction hereinafter described, and particularly pointed out in the claim.

The object of the invention is to provide a novel construction of hook for attaching a watch to a watch-chain in such a manner that an unauthorized person would find difficulty in detaching the watch from the chain, the purpose being to produce a hook affording greater security than the hooks heretofore known for use on the end of watch-chains.

The invention will be fully understood from the detailed description hereinafter presented, reference being had to the accompanying drawings, in which—

Figure 1 is an enlarged front elevation of a hook constructed in accordance with and embodying the invention, the two members of the hook being shown in their open position to receive the ring on a watch, said ring being indicated by dotted lines. Fig. 2 is a like view of same, showing the members of the hook as having been moved toward each other with their lower portions extended beyond each other, which is the second position given to said members in applying the hook to the ring of a watch. Fig. 3 is a like view of same, showing the two members of the hook in their final operative position retaining the watch-ring. Fig. 4 is an edge view of same, showing the ring in dotted lines; and Fig. 5 is a bottom view of same with the ring removed.

In the drawings, 10 designates a suitable metal loop carrying an eye, 11 and having pivotally secured between its sides upon a pin 12 the two members 13 14 of the hook, the latter being designated as a whole 15. The members 13 14 correspond with each other, but are reversely disposed, and each of said members comprises the curved side portion 16 and the lower upwardly and inwardly

curved portion 17, the portion 17 curving inwardly and upwardly from the lower end of the portion 16 and then curving laterally toward the vertical center of the hook, so that when the members 13 14 are folded together, as shown in Fig. 3, the said sections or portions 17 will overlap at their ends and form a transverse bar, below which will be formed an eye or space 18 to inclose the watch-ring 19, the ring 19 when the members 13 14 are folded together being prevented from passing upwardly between the upper portions of the sides 16 thereof and being distinctly confined to the space 18.

In applying the watch-ring 19 to the hook 15 the members 13 14 will be opened outwardly from each other, as shown in Fig. 1, and the ring 19 will have one edge inserted upwardly between the portions 17 of said members and then passed upwardly to the loop 10, as indicated by the dotted lines in Fig. 1, and thereupon the members 13 14 will be moved toward each other and the sections 17 extended outwardly beyond the portions 16 of said members, as shown in Fig. 2, the ring 19 being then confined between the upper portions of said members. After the hook has been given the position shown in Fig. 2 and the watch-ring 19 has been moved downwardly within the elliptical space then formed between the upper portions of the members 13 14, as shown in Fig. 2, the members 13 14 will be moved outwardly to the position shown in Fig. 3, during which movement the watch-ring 19 will slide downwardly until when said members have concluded their movement it will be confined between the lower ends of said members and the sections 17 thereof, said ring 19 being then confined within the space 18, where it will be securely held. When the watch-ring 19 is held by the hook 15 in the manner shown in Fig. 3, it may only with some difficulty be removed therefrom. The removal of the ring 19 from the hook 15 may be accomplished by first folding the members 13 14 of said hook into the position shown in Fig. 2, this naturally resulting in the ring being slid upwardly between the upper portions of said members, as indicated by the dotted lines in Fig. 2, and thereupon while the operator retains the ring 19 in such upper position the members 13 14

of the hook will be moved in a contrary direction or away from each other to the position in which said members are illustrated in Fig. 1, after which the ring 19 will be moved downwardly over one of said members and be permitted to escape between the then separated sections 17 of the hook. In applying the ring 19 to the hook the members 13 14 thereof will therefore first be moved outwardly from each other to the position shown in Fig. 1, the watch-ring then applied, the said members 13 14 then moved toward and partly beyond each other, as shown in Fig. 2, and then outwardly from each other until they attain their normal position, (shown in Fig. 3,) whereupon it will be found that the ring 19 is secured in the space 18 at the lower end of the hook. In removing the ring 19 from the hook the members 13 14 of said hook will first be folded toward and partly beyond each other to the position shown in Fig. 2, this getting the watch-ring 19 above the transverse bar formed by the overlapping sections 17, and then the members 13 14 will be moved to their normal position and at once outwardly to their open position, (shown in Fig. 1,) leaving the sections 17 separated from each other for the escape of the ring 19. The novel feature of the hook resides in the upwardly and inwardly turned sections 17, whereby when the hook is in its normal operative po-

sition the inclosed space 18 is formed for the watch-ring and whereby in applying and removing said ring the several movements above specified must be given to the members 13 14, these movements being in reverse directions and preventing any ready unauthorized detachment of a watch from its chain. 35

What I claim as my invention, and desire to secure by Letters Patent, is— 40

The hook comprising the pivoted members 13, 14, adapted to be moved in a lateral direction toward and from each other beyond their normal operative position and each comprising the curved side portion 16 and the upwardly and inwardly curved portion 17, the portions 17 curving inwardly and upwardly from the lower ends of the side portions 16 and then extending laterally toward each other across the space outlined by said side portions 16 and overlapping each other at their ends to form when the parts of the hook are in normal relation to each other a transverse bar below which is formed the space 18 for the watch-ring; substantially as set forth. 45

Signed at New York, in the county of New York and State of New York, this 30th day of March, A. D. 1903.

CARL H. KEUSCHER.
